UNITED STATES PATENT OFFICE.

EDWIN W. ANDREWS, OF ELMIRA, NEW YORK, ASSIGNOR TO EMANUEL ANDREWS.

INCUBATOR.

SPECIFICATION forming part of Letters Patent No. 508,857, dated November 14, 1893.

Application filed December 1, 1892. Serial No. 453,788. (No model.)

To all whom it may concern:

Be it known that I, EDWIN W. ANDREWS, a citizen of the United States, residing at Elmira, in the county of Chemung and State of New York, have invented certain new and useful Improvements in Incubators; and I do hereby declare the following to be a full, clear, and exact description of the invention, which will enable others skilled in the art to which it appertains to make and use the same.

My present invention has reference to various new and useful improvements in the construction and in the operation of incubators and the particular objects which I seek to obtain by the use of my said invention is to provide and to produce an incubator of novel construction wherein certain advantages of operation are to be obtained. Specifically speaking, these advantages consist primarily in the production of an incubator which will be more compact in size and effective in operation than those incubators which have been heretofore made, and wherein large radiating drums and water are pans made use of.

Another advantage is in the novel means I have employed in heating the interior of the incubator, or incubating chamber, and in supplying thereto the proper amount of moisture, all of which I will more fully hereinafter describe and claim.

For a better comprehension of my improved incubator attention is directed to the accompanying drawings, forming a part of this specification, and in which—

Figure 1 is a top view of the incubator with the cover and lamp removed and showing a portion of the water drum in section. Fig. 2 is a vertical sectional view of the incubator showing the heating apparatus in elevation; Fig. 3 an enlarged elevation of the water drum, showing the air valve therein; Fig. 4 a top view of the lamp burner and one form of regulating mechanism of the same. Fig. 5 is an elevation of Fig. 4.

In all of the above views, corresponding parts are designated by the same letters of reference.

A represents the ordinary incubating chamber, which is to be supported in any way, but

preferably on suitable legs B. This incubating chamber is provided at one side with the usual doors, having glass doors therein, through which the interior of the incubating chamber may be observed, and by which the amount of moisture necessary in the incubator may be determined by the extent of the condensation thereon, as will be explained hereinafter.

C is a partition mounted within the incubating chamber near one end thereof and extending from top to bottom and from side to side, so as to form a smaller chamber C' at one end.

D is another partition arranged similarly to the partition C and near the other end of the incubating chamber, except that it is provided with an open space beneath its lower end through which the air may circulate out through the opening a.

E is a water drum which is placed within the chamber C' at the upper part thereof, and which is preferably made of sheet metal or cast metal in the form of a hollow parallelogram. This water drum is provided at its central part with a vertical partition b extending from the top to the bottom of said water drum, and with short connecting partitions b', by means of which a secondary chamber F will be formed within said water drum.

G are metal pipes which extend horizontally out from the secondary chamber F near its lower part and provided at their outside ends each with a double elbow c, which are connected to the water drum by pipes H which enter the latter near its bottom. These pipes G and H, being arranged as I have just described near the upper end of the incubating chamber, will not interfere in any way with the proper distribution of the eggs therein.

The heating apparatus for my improved incubator is located preferably at the end thereof, adjacent to the water drum. This heating apparatus consists of an ordinary lamp d having, preferably, a metallic chimney d', which flares outwardly. Mounted directly above this chimney d' is a water tank e, having a flaring passage e' therein, which constitutes practically a continuation of the

chimney *d'*. This water tank *e* is provided at one side with a faucet *f* by which the water may be withdrawn from the apparatus.

Mounted a short distance above the water tank *e* is a smaller cylindrical water tank *g* the top of which is on a level intermediate between the top of the water drum *E* and the radiating pipes *G* and *H*. This cylindrical water tank *g* is provided at its top with an opening having a screw cap *g'* thereon, through which the desired amount of water may be introduced into the apparatus. The water tank *g* communicates with the water tank *e* by means of small conducting pipes *h*. The proper supply of air to the lamp *d* is obtained by means of small holes *i* which are made within the chimney *d'*. The upper cylindrical water tank *g* communicates directly with the water drum *E* by means of a horizontal pipe *j* which passes through the end wall of the incubating chamber and enters the water drum near its bottom. The water tank *e* communicates with the secondary chamber *F* by means of a right angled pipe *k* which enters the water drum *e* at or near its lower end and extends into the secondary chamber *F* so as to be flush with the bottom of said secondary chamber, or approximately so. These pipes *j* and *k* serve to support the water tanks *e* and *g* so that the latter will be independent of the lamp *d* and will bear in no way thereon. The lamp *d* can therefore be removed at any time for the purpose of filling, as may be desired.

Extending up from the bottom of the incubating chamber and entering the secondary chamber *F* are air supply pipes *l*, which extend up into said secondary chamber *F* to a point near its upper end so as to be above the level of the water within the same. The said secondary chamber *F* is provided on its inner wall with a plurality of holes *m*, *m*, which are placed above the level of the water in the secondary chamber and which open into the incubating chamber. Mounted upon the same wall of the secondary chamber, and in the incubating chamber above the pipes *G* and *H*, is a slide *I*, held in guides *m'* and provided with a handle *I'* extending outside of the incubating chamber and by which the said slide *I* may be moved back and forth. The said slide *I* is provided with openings therein, corresponding in size and location with the openings *m*.

A convenient form of regulating mechanism which I have designed for use in connection with the incubator will now be described.

J is a thermostatic bar which extends obliquely across the incubating chamber directly beneath the radiating pipes *G* and *H* and abutting against the blocks *n*, *n*. The said thermostatic bar *J* normally has a slight curve upward or downward, as shown in Fig. 2.

The preferable material of which I desire to construct the thermostatic bar *J* is hard rubber, because I have found in experimenting with my improved incubator that that

material is extremely susceptible to slight changes in temperature but it is evident that any other suitable material may be substituted, such, for example, as brass or a combination of brass and hard rubber. Extending up from the central portion of the thermostatic bar *J* is a metal rod *o*, leading up to the top of the incubating chamber and engaging with one end of the lever *K*, which is fulcrumed, as shown, close to the rod *o*. The said rod *o* is screw-threaded at its upper end and is provided on that portion with an adjusting nut *o'* by which the relative relations between the lever *K* and the thermostatic bar *J* may be regulated at will. Pivoted to the outside end of the lever *K* is a rod *L* which extends downward and is movably connected in any way with the end of the lever *p*, fulcrumed preferably near said end and onto the burner of the lamp. The other end of said lever *p* connects rigidly with the crank arm *Q*, which extends horizontally across the lamp burner with its crank portion surrounding the wick. The ordinary wick tube is surrounded with the movable shield *r*, provided with wings *r'* having openings therein, through which the crank portions of the arm *Q* extend. By means of the system of levers which I have just described, it will be observed that a very slight movement of the thermostatic bar will cause a correspondingly lengthy movement upward and downward of the shield *r'* so as to affect the flame to a greater or less extent.

The above described heat regulating device will not be claimed herein, the Commissioner of Patents, having required me to file a divisional application thereon, and it will, therefore, be understood that my improved incubator is entirely independent of said heat regulating device, and that any suitable heat regulating device may be used in connection therewith. I consider that the said heat regulating device is however, a very convenient and appropriate device for use with my improved incubator.

M represents the egg rack, which is supported on cleats *s*, *s*, secured to the partitions *C* and *D* and arranged beneath the radiating pipes *G* and *H*.

It will be evident that the height of the incubating chamber may be increased as desired, and that a corresponding number of egg trays may be used.

The operation of my device and of the improved thermostatic regulator therefor will now be described.

A suitable quantity of water is poured into the water chamber *g* until there is a sufficient height therein to cover the pipe *j*. This water will therefore entirely fill the water tank *e*, the pipe *k*, the radiating pipes *G* and *H*, the connecting pipe *j* and will partially fill the water drum *E*, the secondary chamber *F*, and the water tank *g*. The lamp being lighted the heat therefrom will ascend the flaring passage *e'* and will flow against the bottom of the

water tank, so as to heat the water in both tanks *e* and *g*. This water, by a well known physical law, will begin to circulate through the pipe *j* and water drum *E*, the pipes *G* and *H*, the double elbows, *C*, the pipes *G* and *G*, the secondary chamber *F*, and the pipe *k*, back to the water tank *e*. The hot water within the radiating tubes *G* and *H* will therefore heat the interior of the incubating chamber to the desired temperature. At the same time that the water is circulating between the radiating pipes *G* and *H*, a suitable supply of air enters the air pipes *l* from the bottom of the incubating chamber and passing up into the top of the secondary chamber *F* above the water line and coming into contact with the water therein, will pass out through the openings *m* and will enter the incubating chamber in a thoroughly moistened condition. This moistened air will pass down through the incubating chamber around the eggs on the egg tray and under the bottom of the partition *D*, and will escape through the vent *a*. The moistened air coming into contact with the glass doors of the device will condense thereon and according to the amount of this condensation which can be observed from the outside of the device, a person skilled in the operation of my improved incubator can readily determine whether or not the proper amount of moistened air is entering the incubator. If too great an amount of air is passing over the eggs the handle *I'* of the slide valve is moved slightly, so that the holes in the side of said valve are thrown out of their corresponding relations with the holes in the secondary chamber *F*, so that the supply of air is decreased. The supply of moistened air in the incubating chamber can be so regulated that either a very small quantity will pass through or a very great quantity, as will be necessary, according to the condition of the atmosphere of the room in which the incubator is to be placed, and in this connection it is to be noticed that in incubators wherein a water tank is made use of, there is no provision for regulating the supply of moistened air within the same. Often there is too much moisture in the air for the proper incubation of the eggs and at other times there is not enough moisture for this purpose. The proper temperature which is to be maintained in the box is first determined by experimenting with the adjusting screw *o'* if the heat regulating mechanism described above is used and when once obtained, no further adjustment will be necessary. Should the temperature within the incubating chamber begin to rise the thermostatic bar *J* will expand and will curve or "buckle" at its center causing the rod to rise slightly and the outside end of the lever *K* to be depressed to a greater extent and allow the connecting rod *L* to be correspondingly moved and the short lever *p* will be elevated at its longer end, so as to carry the shield *r* upward and surround the

flame to a greater or less extent. The shield *r* on thus being elevated will smother the flame to a certain extent and the heat thereof will be decreased until the increased heat which caused the thermostatic bar to be operated will be thoroughly counteracted.

Having now described my invention, what I claim as new therein, and desire to secure by Letters Patent, is as follows:

1. In an incubator, the combination with an incubating chamber; of the water drum *E*, therein; the lamp *d*, outside of said incubating chamber; the water tanks *e* and *g*, above said lamp, and communicating with each other the tank *g*, communicating with the water drum *E*; the radiating pipes *H*, in said incubating chamber, and communicating with said water drum *E*; and the radiating pipes *G*, in said incubating chamber, connecting with said radiating pipes *H*, and communicating with said tank *e* by means of the pipe *k*, substantially as set forth.

2. In an incubator, the combination with an incubating chamber of the water drum *E* and secondary chamber *F*, therein; the radiating pipes *H* communicating with said water drum, the radiating pipes *G*, *G*, communicating with said secondary chamber; the elbows *C*, *C*, connecting said pipes *G* and *H*, the air pipes *l*, *l*, extending up into said secondary chamber *F* above the water line; the water tank *g* communicating with said water drum *E* and the tank *e*, communicating with said secondary chamber *F*; the pipes *h*, *h*, connecting said water tanks *e* and *g*, the lamp *d*, beneath the said water tank *e*, substantially as described.

3. In an incubator, the combination with an incubating chamber of the water drum, the secondary chamber *F* within the same; the radiating pipes *H*, *H*, communicating with said water drum; the pipes *G*, *G*, communicating with said secondary chamber *F*; the elbows *C*, *C*, connecting said pipes *G*, *H*; the air pipes *l*, *l*, entering said secondary chamber above the water line; the openings *m*, *m*, in said secondary chamber and entering the incubating chamber; the slide valve, *I*, having holes therein, corresponding with holes in the water tank *g*, communicating with said water drum *E*; the water tank *e* communicating with said secondary chamber *F*; the pipes *h*, *h*, connecting said water tanks *e* and *g*; and the lamp *d*, beneath said water tank *e*.

4. In an incubator the combination with the incubating chamber of the water drum, the secondary chamber *F* therein; the pipes *H*, *H*, communicating with said water drum *E*; the pipes *G*, *G*, communicating with said secondary chamber *F*; the elbows *C*, *C*, connecting said pipes *G* and *H*, the water tanks *e* and *g*, the pipes *h*, *h*, connecting said water tanks *e* and *g*; the lamp *d*, beneath said water tank *e*; the chimney *d'* for said lamp; the openings *i*, *i*, within said chimney, and the flaring openings *e'* extending up through said tank *e*.

- and opening beneath the bottom of the water tank *g*, substantially as described.
5. In an incubator, the combination with an incubating chamber of the partitions *C* and *D*; the openings beneath the partition *D*; the vent *a*; the egg rack *M* supported by said partitions *C* and *D*; and radiating pipes in upper part of said incubating chamber, substantially as described.
- 10 6. In an incubator, consisting of an incubating chamber, provided with the partitions *C* and *D* therein; the opening beneath the partition *D*; the vent *a*; the egg rack *M* sup-
- ported by said partitions *C* and *D*; radiating pipes near the upper end of said incubating chamber, the heating apparatus at one end of said incubating chamber, the said radiating pipes connecting said heating apparatus and a heat regulating device, substantially as described.
- 15 20 In testimony whereof I affix my signature in presence of two witnesses.

EDWIN W. ANDREWS.
